PERCUSSIVE TOOL VALVE

William A. Smith, Jr., North Arlington, N. J., and Herman J. Schorie, Astoria, N. Y., assignors to Worthington Pump and Machinery Corporation, New York, N. Y., a corporation of Virginia

Application March 1, 1934, Serial No. 713,515

7 Claims. (Cl. 121—19)

This invention relates to percussive tools and more particularly to valves therefore.

An object of the invention is to provide a valve for controlling the distribution of the pressure fluid in a percussive tool, which valve is positive and quick in action and one which will provide a heavy blow of the hammer piston of the tool and will cut down the consumption of pressure fluid in proportion to the amount of work performed.

With these and other objects in view as may appear from the accompanying specification, the invention consists of various features of construction and combination of parts, which will be first described in connection with the accompanying drawing, showing a balancing structure of the preferred form, and the features forming the invention will be specifically pointed out in the claims.

20 In the drawing: Fig. 1 is a fragmentary longitudinal section through a percussive tool showing the improved valve.

25 Fig. 2 is a fragmentary longitudinal section similar to Fig. 1 showing the valve in a different position.

Fig. 3 is an enlarged longitudinal section through the valve and valve chest.

Fig. 4 is an isometric view of the valve.

20 Referring more particularly to the drawing, the improved percussive tool comprises a cylinder 1 having a piston chamber 2 therein in which the piston 3 reciprocates. A back head 4 is attached in the usual manner to the cylinder 1 and has a valve chest 5 therein in which the valve 10, which controls the distribution of pressure fluid to the piston chamber 2 is mounted.

25 Pressure fluid is delivered to the valve chest 5 through the port 6, into the annular channel 7 formed in the back head 4. The delivery of the pressure fluid to the channel 7 is controlled by the usual type of throttle valve 8.

30 The valve 10, which reciprocates in the valve chest 5 comprises a cup-like body 11, the forward end of which opens through the passage 9 into the piston chamber 2, and consequently the inner sur-

35 face 12 of the transverse wall 13 of the body 11 is exposed to compression from the piston chamber 2 for co-operating with the pressure fluid against the pressure area 14 formed on the body 11 by the annular channel 15. The annular channel 15 is cut in the body 11 a short distance rearwardly from the forward open end of the body. The pressure fluid is delivered to the annular channel 15 by a plurality of radially spaced

ports 16 formed in the valve chest 5. The body 11 is undercut at its forward open end to provide the chamber 17 and this undercut together with the annular channel 15 form a flange 18. The flange 18 is provided with a plurality of perforations 19 formed therein through which pressure fluid passes into the annular chamber 17. The under-surface of the flange 18 forms a pressure area against which live pressure fluid presses for co-operating with the pressure fluid against the wall 14 and the compression against the wall 12 for holding the valve 10 in its rearward position as shown in Fig. 2 of the drawing, thereby permitting the live pressure fluid to pass through the port or passage 9 into the rear end of the piston chamber 2 for driving the hammer piston 3 forwardly.

35 As the hammer piston 3 moves forwardly and passes the exhaust port 20 formed in the cylinder 1 the pressure against the flange 18, pressure area 14 and pressure area 12 is relieved and the forward end of the piston chamber 2 which is opened through the ports 21 delivers compression from the port 22 into the chamber 23 and thence on the rear side of the transverse wall 13 of the body 11 within the ring flange 25 which projects rearwardly from the transverse wall 13. The portion of the transverse wall exteriorly of the outer periphery of the ring flange 25 is exposed to pressure fluid in the chamber 26. The chamber 26 has communication with the annular channel 7 through ports 27. Thus when the pressure in the rear end of the cylinder is relieved, the pressure of compression against the pressure area 24 and the pressure of pressure fluid against the rear surface of the transverse wall 13 will move the valve 10 to its forward position as shown in Figs. 1 and 3 of the drawing and will move the rear surface of the transverse wall 13 away from the seat 28. When the valve body 11 is moved away from the seat 28 the pressure fluid will pass through the clearance space 30 into the chamber 23 and outwardly through the ports 22 and 21 into the forward end of the piston chamber 22 for driving the piston hammer 3 rearwardly.

40 The cup-like body 11 of the valve 10 has an annular shoulder 31 formed thereon which is exposed to atmospheric pressure in the annular chamber 32 formed in the valve chest 5. A port 33 extends through the valve chest 5 and has communication with the atmosphere through flats or channels 34 formed on or in the valve chest so that the flange 31 will be exposed to atmospheric pressure for assisting in holding the

110

valve 10 seated in its forward position and also for assisting in moving the valve 10 into its forward position when the pressure is relieved in the rear end of the piston chamber 2.

5 As the piston 3 moves rearwardly and passes the exhaust port 20 the pressure in the forward end of the piston chamber 2 is relieved and the compression in the rear end of the piston chamber building up and engaging against the pressure area 12 co-operates with the pressure of the pressure fluid against the flange 18 and pressure area 14 to overcome the atmospheric pressure on the shoulder 31 and the pressure of the pressure fluid on the rear surface of the transverse wall 13 for moving the valve 10 into its rearward position as shown in Fig. 2 to permit the pressure fluid to pass through the passage 9 into the rear end of the piston chamber.

It will be understood that the invention is not to be limited to the specific construction or arrangement of parts shown but that they may be widely modified within the invention defined by the claims.

What is claimed is:

25 1. In a percussive tool, the combination of a cylinder having a piston chamber therein, a piston in said chamber, an exhaust port in the cylinder, a valve chest having a valve chamber, inlet passages leading from the valve chamber to the piston chamber, a valve in said chamber comprising a cup-like body including a cylindrical wall and a transverse wall, said body having an annular groove formed therein providing a flange, ports leading to said groove for supplying pressure fluid thereto, the rear wall of said groove forming a pressure surface exposed to pressure fluid and the forward surface of said transverse wall being exposed to compression from the cylinder for throwing the valve in one direction, a part of the rear of said transverse wall being exposed to pressure fluid and the remaining portion of the rear side of said transverse wall being exposed to compression for throwing the valve in the opposite direction.

45 2. In a percussive tool, the combination of a cylinder having a piston chamber therein, a piston in said chamber, an exhaust port in the cylinder, a valve chest having a valve chamber, inlet passages leading from the valve chamber to the piston chamber, a valve in said chamber comprising a cup-like body including a cylindrical wall and a transverse wall, said body having an annular groove formed therein providing a flange, ports leading to said groove for supplying pressure fluid thereto, the rear wall of said groove forming a pressure surface exposed to pressure fluid and the forward surface of said transverse wall being exposed to compression from the cylinder for throwing the valve in one direction, a part of the rear surface of said transverse wall being exposed to pressure fluid and the remaining portion of the rear side of said transverse wall being exposed to compression for throwing the valve in the opposite direction, and an annular shoulder formed on said cylindrical wall and exposed to atmospheric pressure for assisting in throwing said valve in one direction.

65 3. In a percussive tool, the combination of a cylinder having a piston chamber therein, a piston in said chamber, an exhaust port in the cylinder, a valve chest having a valve chamber, inlet passages leading from the valve chamber to the piston chamber, a valve in said chamber comprising a cup-like body including a cylindrical wall and a transverse wall, said body having

an annular groove formed therein providing a flange, ports leading to said groove for supplying pressure fluid thereto, the rear wall of said groove forming a pressure surface exposed to pressure fluid and the forward surface of said transverse wall being exposed to compression from the cylinder for throwing the valve in one direction, a part of the rear surface of said transverse wall being exposed to pressure fluid and the remaining portion of the rear side of said transverse wall exposed to compression for throwing the valve in the opposite direction, and an annular shoulder formed on said cylindrical wall and exposed to atmospheric pressure for assisting in throwing said valve in one direction, said flange provided with ports to admit pressure fluid to the rear end of the cylinder.

4. In a percussive tool, the combination of a cylinder having a piston chamber therein, a piston in said chamber, an exhaust port in the cylinder, a valve chest having a valve chamber, inlet passages leading from the valve chamber to the piston chamber, a valve in said chamber comprising a cup-like body including a cylindrical wall and a transverse wall, said body having an annular groove formed therein providing a flange, ports leading to said groove for supplying pressure fluid thereto, the rear wall of said groove forming a pressure surface exposed to pressure fluid and the forward surface of said transverse wall being exposed to compression from the cylinder for throwing the valve in one direction, a part of the rear surface of said transverse wall being exposed to pressure fluid and the remaining portion of the rear side of said transverse wall being exposed to compression for throwing the valve in the opposite direction, and a ring formed on the outer surface of said transverse wall and co-operating with adjacent surfaces of said valve chest to provide a restricted clearance space for controlling the delivery of pressure fluid to the forward end of the cylinder.

5. In a percussive tool, the combination of a cylinder having a piston chamber therein, a piston in said chamber, an exhaust port in the cylinder, a valve chest having a valve chamber, inlet passages leading from the valve chamber to the piston chamber, a valve in said chamber comprising a cup-like body including a cylindrical wall and a transverse wall, said body having an annular groove formed therein providing a flange, ports leading to said groove for supplying pressure fluid thereto, the rear wall of said groove forming a pressure surface exposed to pressure fluid and the forward surface of said transverse wall being exposed to compression from the cylinder for throwing the valve in one direction, a part of the rear surface of said transverse wall being exposed to pressure fluid and the remaining portion of the rear side of said transverse wall being exposed to compression for throwing the valve in the opposite direction, a ring formed on the outer surface of said transverse wall and co-operating with adjacent surfaces of said valve chest to provide a restricted clearance space for controlling the delivery of pressure fluid to the forward end of the cylinder, and an annular shoulder formed on said cylindrical wall and exposed to atmospheric pressure for assisting in throwing said valve in one direction.

6. In a percussive tool, the combination of a cylinder having a piston chamber therein, a piston in said chamber, an exhaust port in the cylinder, a valve chest having a valve chamber, inlet passages leading from the valve chamber

to the piston chamber, a valve in said chamber comprising a cup-like body including a cylindrical wall and a transverse wall, said valve chest provided with a chamber outwardly of the outer 5 side of said transverse wall and with ports for supplying pressure fluid to said chamber, and a ring flange formed on the rear surface of said transverse wall and cooperating with adjacent surfaces of said valve chest to provide a restricted 10 clearance space for controlling the delivery of pressure fluid to the forward end of the cylinder.

7. In a percussive tool, the combination of a cylinder having a piston chamber therein, a piston in said chamber, an exhaust port in the cylinder, 15 a valve chest having a valve chamber, inlet passages leading from the valve chamber to the piston chamber, a valve in said chamber comprising a cup-like body including a cylindrical wall and a transverse wall, said body having an annular groove formed therein providing a flange, ports leading to said groove for supplying pressure fluid thereto, the rear wall of said groove forming a 20 pressure surface exposed to pressure fluid and the

forward surface of said transverse wall being exposed to compression from the cylinder for throwing the valve in one direction, a part of the rear surface of said transverse wall being exposed to pressure fluid and the remaining portion 80 of the rear side of said transverse wall being exposed to compression for throwing the valve in the opposite direction, a ring formed on the outer surface of said transverse wall and co-operating with adjacent surfaces of said valve chest to provide a restricted clearance space for controlling the delivery of pressure fluid to the forward end of the cylinder, and an annular shoulder formed on said cylindrical wall and exposed to atmospheric pressure for assisting in throwing said 85 valve in one direction, the rear surface of said transverse wall inside of said ring forming a pressure area subjected alternately to compression from the piston chamber for assisting in throwing the valve in one direction and to pressure fluid for holding the valve in one position. 90 95
